SULPHONATED ALIPHATIC HYDROCARBON
DERIVATIVES, USEFUL AS WETTING AND
CLEANSING AGENTS

ware

No Drawing. Application May 28, 1932,
Serial No. 614,290

15 Claims. (Cl. 260—156)

This invention relates to chemical compounds, more particularly surface active substances and a process for the manufacture thereof.

As is well known, surface active compounds which possess cleaning, wetting and dispersing properties may be advantageously used in the various industries, for example, the textile and leather industries, for a wide variety of purposes. Thus, surface active compounds such as soaps, 10 that is, the sodium salts of the higher fatty acids, find a wide application in the laundering, dyeing and finishing of textiles. Soaps are characterized by the disadvantage, however, that they are not soluble in acidic solutions since the alkali metal salts of the fatty acids are converted into the insoluble fatty acids. Soaps are also precipitated in strongly alkaline solutions. Furthermore, in hard water the alkali metal salts of fatty acids are precipitated as the insoluble alkaline earth 20 metal salts, such as those of calcium, magnesium and the like.

While other surface active substances have been prepared such as, for example, the Turkey red oils (that is, the reaction products of castor oil with concentrated sulphuric acid at relatively low temperatures) which are more soluble than soaps in the presence of mineral acids and hard water, these substances are generally much less effective detergents than the soaps they are designed to replace.

It is an object of the present invention to produce new chemical products which are highly surface active, are water soluble, and possess good wetting and detergent power even in relatively 35 strongly alkaline or acidic solutions. A further object is the production of surface active compounds having relatively soluble alkaline earth metal salts and which, therefore, are adapted for use in hard water. A still further object of the 40 invention is the provision of a new and improved process for producing the above described compounds. Another object is the production of these surface active compounds directly in a high state of purity. A further object is the production of 45 compounds of the character described by a process involving a series of reactions which proceed with great smoothness and almost theoretical yields. Further objects will appear hereinafter.

These objects are accomplished according to 50 this invention whereby products especially useful as detergent, wetting and dispersing agents are produced by reacting unsaturated aliphatic hydrocarbons, containing 8 or more carbon atoms and having a double bond at the end of the chain, 55 with a halogen sulphonic acid in the presence of

a halogenating catalyst and treating the reaction product with a hydrolyzing agent.

While the invention is subject to considerable variation and modification in the manner of its practical application, particularly as regards the kind and proportions of the reactants and the exact method of procedure, the following examples, in which the parts are by weight, will serve to illustrate some of the products falling within the invention and how they may be prepared. 10

Example I

Twenty parts 1-2-octadecylene obtained by dehydrating primary n-octadecyl alcohol were dissolved in about 80 parts of carbon tetrachloride. 15 Approximately one-tenth part of pyrolusite was suspended in the solution which was then cooled to about 0-5° C. Twelve parts of chlorosulphonic acid were added slowly to the mixture with agitation, the resultant mixture being maintained at 20 the above low temperature for a period of about two more hours. At the end of this time the temperature was allowed to rise to about 20-25° C. After standing at this temperature for 12-14 hours the liquid was poured into water, neutralized with 20% sodium hydroxide solution and about 6 parts of excess sodium hydroxide added. The product was boiled for an hour to hydrolyze 25 it and to remove carbon tetrachloride. The resultant solution was neutralized with 10% sulphuric acid solution and then evaporated to a small volume. The product was isolated by precipitating the inorganic salts with an excess of ethyl alcohol, filtering the alcohol solution and evaporating off the alcohol and water. The resultant product was a light brown oil, clearly 30 soluble in water, possessing high surface activity and characterized by unusual stability in combination with marked wetting, cleaning, and dispersing power even in strongly acid or alkaline 35 solutions. The weight of product obtained in this way was 32.5 parts.

Example II

1-2-octadecylene was treated with chlorosulphonic acid and the resultant product was hydrolyzed as described in Example I, except that one-tenth part of iodine was used as a catalyst instead of pyrolusite. The yield of product obtained by extracting with alcohol was about 30.8 parts. An aqueous solution of the product was perfectly 45 clear and possessed excellent detergent and wetting properties. The product was also stable and was characterized by marked cleaning, dispersing and penetrating power in solutions containing 50 55

more than 10% of hydrochloric acid and in solutions containing more than 10% of sodium hydroxide. In fact no tendency towards instability was noticed in any alkaline, neutral or 5 acidic aqueous solutions.

Example III

The process of Example I was carried out in the presence of about one-tenth part of cuprous 10 chloride instead of pyrolusite. The yield of product obtained by extraction with alcohol was about 25.5 parts and its properties were similar to those of the substances produced as described in Examples I and II.

15 For comparison, the procedure described in Examples I, II and III was carried out a number of times without a catalyst, all other conditions of operation and proportions of materials being the same. In marked contrast with the 20 reaction where a catalyst was used, it was observed that after hydrolysis and neutralization of the hydrolyzed product with the 10% sulphuric acid solution an oily liquid formed in the reaction mixture. This oily substance was removed and the 25 remaining liquid evaporated to a small volume and extracted with alcohol as described in Example I. The average yield of product was about 23.0 parts. This product likewise was soluble in water and possessed good wetting, cleaning and 30 dispersing powers, even in relatively strongly acidic or alkaline solutions. As will be apparent, however, the yield was not so high as that obtained from the reaction with a catalyst. Thus the increase of yield obtained by the procedure 35 of Example I, was about 41%. Actually the increase in yield was probably greater than this since the products obtained by the use of catalysts were purer than those obtained without catalysts. This was shown by the fact that the 40 aqueous solutions of the products obtained with catalysts were perfectly clear while solutions of the products obtained without a catalyst were cloudy, the cloudiness probably indicating incomplete removal of the by-product oily material 45 formed during the hydrolysis. Furthermore, the products obtained from the reaction with a catalyst were more effective wetting agents than the products obtained without catalysts.

The unsaturated hydrocarbons employed in 50 accordance with the present invention may be any aliphatic unsaturated hydrocarbons containing 8 or more carbon atoms and having a double bond at the end of the chain. Mixtures of such hydrocarbons may be employed; or, starting materials 55 may be mixtures containing unsaturated hydrocarbons of the character above described and olefines in which the double linkage is not at the end of the chain. In general, the results are more desirable, however, the larger the proportion 60 of hydrocarbons having a double linkage at the end of the chain. The aliphatic unsaturated hydrocarbons may be of the straight or branched chain type. Generally speaking, the straight chain hydrocarbons having a single double bond 65 at the end of the chain are preferred. Hydrocarbons of this kind may be obtained in any suitable manner, for example, by dehydrating the primary alcohols obtained by hydrogenating fatty acids or their esters, e. g. those contained in 70 palm oil, tallow, coconut oil and olive oil. Branched chain unsaturated hydrocarbons falling within the invention may likewise be obtained in any desirable manner, for example, by polymerizing relatively short chain olefines or by dehydrating synthetic higher alcohols or mixtures 75

thereof, e. g. those produced by the hydrogenation of carbon oxides under elevated temperatures and pressures. Where branched chain hydrocarbons are employed the better results are obtained the shorter the side chain.

5 In practicing the invention the halogen sulphonate acids preferably employed are chlorsulphonic acid and bromsulphonic acid. The proportions of halogen sulphonic acid employed may vary within relatively wide limits depending largely upon the nature of the unsaturated hydrocarbon treated and the products desired. In general, it is preferable to employ about 1-2 moles of halogen sulphonic acid for each double bond per mole of an unsaturated hydrocarbon. In 10 certain cases, however, it may be desirable to use larger or smaller proportions of the halogen sulphonic acid, it being understood that the desired reaction proceeds whether a small or large amount of sulphonic acid is employed.

20 As indicated by the examples, the reaction of the halogen sulphonic acid with the unsaturated hydrocarbon is preferably effected in a suitable liquid medium, that is to say, a medium which is liquid at the temperature of the reaction and is inert to the reactants and products or does not affect the reaction unfavorably. It may or may not be a solvent for the reactants and/or products. As examples of such media may be mentioned carbon tetrachloride, ethylene-dichloride, 30 trichlorethylene, tetrachlorethane, chloroform, liquid sulphur dioxide, diethyl ether, acetic anhydride, propionic acid and propionic anhydride. Generally speaking, we prefer to employ solvent or suspension media having a boiling point below 35 about 100° C., and especially desirable results have been obtained with carbon tetrachloride.

40 The catalyst employed in accordance with the invention may be any catalyst favoring the halogenation of carbon compounds. By halogenation is meant the action of a free halogen on a hydrocarbon whereby a hydrogen atom in the hydrocarbon is replaced by a halogen atom. The catalyst should preferably be soluble in the reaction mixture and, furthermore, should preferably be a compound which does not give rise to oxidation reactions. As examples of halogenating catalysts may be mentioned antimony trioxide, antimony pentoxide, antimony trichloride, antimony pentachloride, antimony sulphate, 50 cuprous chloride, cupric oxide, cuprous oxide, cupric sulphate, cupric acetate, manganese dioxide, pyrolusite, manganous sulphate, manganese oxide, ferric chloride, ferrous sulphate, ferric sulphate, ferric oxide, ferrous oxide, magnete, vanadium pentoxide, sodium vanadate, vanadyl sulphate, aluminum chloride, aluminum sulphate, cuprous iodide, sodium iodide, potassium iodide and free iodine. It will be recognized that the results obtained with the foregoing catalysts may differ widely depending largely upon the specific reactants and conditions of operation. We have found that the reaction proceeds very smoothly and the final products are exceptionally light in color when unsaturated hydrocarbons of the character herein described are reacted with chlorsulphonic acid in the presence of a chlorinating catalyst. Of the various chlorinating catalysts with which we have practiced this preferred embodiment of the invention, the 60 results obtained with pyrolusite and iodine have been very highly advantageous.

65 The amount of catalyst employed may vary considerably depending more or less upon the nature thereof and that of the reactants, but as 70 75

a general rule desirable results have been obtained by the addition of catalysts to the reaction mixture in proportions corresponding to about 0.1-5.0% by weight of the reacting substances.

5 The time allowed for the reaction between the halogen sulphonic acid and the unsaturated hydrocarbon to take place will depend largely upon the nature of the reactants, the catalysts and the conditions of temperature. Under ordinary 10 operating conditions it may vary from about 2 to 48 hours. In practice, however, this reaction is ordinarily allowed to proceed until a sample of the product boiled with a hydrolyzing agent is soluble in water.

15 While the temperature maintained in effecting the reaction with the halogen sulphonic acid may vary within relatively wide limits, the temperature employed should preferably be below that giving rise to decomposition, resinification or polymerization of the reactants and products. In general, it is preferable to maintain the temperatures in this step of the process below about 50° C. and preferably within the range of about -10-+35° C. Ordinarily, higher temperatures tend to yield darker products.

20 The hydrolysis of the product resulting from the reaction of the halogen sulphonic acid and the unsaturated hydrocarbon may be effected in a number of ways. Thus, water may be added until the acid concentration is relatively low and the resultant product boiled; or the sulphonated product may be neutralized and then heated with a hydrolyzing agent. In some cases it may be possible to effect hydrolysis, at least in part, by merely neutralizing the reaction product of the halogen sulphonic acid and unsaturated hydrocarbon with an aqueous alkaline reagent and then boiling the resultant product. Hydrolyzing agents which are suitable for the 25 process of the invention are mineral acids, e. g. hydrochloric, sulphuric and the like, or alkaline reagents, e. g., alkali metal and alkaline earth metal hydroxides. In practice, we prefer to neutralize the sulphonated product with an aqueous 30 solution of an alkali metal hydroxide, preferably sodium hydroxide, and heat the product with a further quantity of the alkali metal hydroxide to effect hydrolysis.

35 The amount of alkaline reagent employed for neutralization and hydrolysis of the sulphonation product should preferably correspond to at least one equivalent for every equivalent of halogen sulphonic acid used. Thus, if the reaction with the unsaturated hydrocarbon is carried out 40 by means of one mole of chlorsulphonic acid, neutralization and hydrolysis of the product may be effected with two moles of sodium hydroxide. In general, it is preferable to use an excess of the alkaline reagent over the amount required for 45 neutralization and hydrolysis.

50 The amount of water present during the hydrolysis may vary widely. Very satisfactory results are obtained, however, when the suphonated product is heated with solutions of mineral acids, alkali metal hydroxides or alkaline earth metal hydroxides having concentrations of about 2-20%.

55 The temperature of the hydrolysis is subject to considerable variation but should preferably be above 50° C. and below the temperature at which the reactants or products decompose. A temperature of about 100° C. is normally satisfactory for carrying out the hydrolysis. If a solvent or suspension medium is used in the first step of the 60 process, it is preferably removed prior to or dur-

ing hydrolysis by evaporation, steam distillation or in any other suitable manner. The time allowed for the hydrolysis is preferably determined by allowing the hydrolytic action to proceed until a sample of the product dissolves in 5 water.

65 Products of some value as emulsifying agents may be obtained by reacting the unsaturated aliphatic hydrocarbons with a halogen sulphonic acid in the presence of a halogenating catalyst as above described, and then merely neutralizing the reaction product without hydrolyzing it. These intermediate products may also possess some wetting and detergent power, particularly if relatively short chain unsaturated hydrocarbons are employed. In general, however, these products are insoluble or only slightly soluble in 15 water.

70 The final products produced in accordance with the invention, on the other hand, are soluble in water. Furthermore, they are highly surface active and possess excellent cleaning, wetting and dispersing properties. They are particularly valuable from a commercial standpoint because of their stability in all kinds of acidic, 25 alkaline and neutral aqueous media and are distinguished from any products previously prepared by their stability in strong acids and alkalies. Because of these characteristics our new products have an unusually wide application for 30 industrial purposes. Since they may be used in acid, neutral or alkaline baths they are especially well adapted for the laundering, dyeing, bleaching, carbonizing, mercerizing and finishing of 35 textiles. They are also well adapted for use as emulsifying and solubilizing agents for water immiscible or only slightly miscible solvents. They may be employed as such or in combination with water miscible or immiscible alcohols, ketones or other additional materials, such as washing, 40 cleansing, emulsifying and wetting agents, e. g. trisodium phosphate, Turkey red oils, soaps, aliphatic or aromatic sulphonic acids, such as alkylated naphthalene sulphonic acids, mineral oil sulphonic acids, sulphonated derivatives of abietic acid, sulphur esters, saponin and aliphatic and aromatic acid amides, such as sodium taurocholate or sodium salts of analogous acid amides. When 45 employed alone or in combination with other materials such as those mentioned above they find wide application as pasting, cleansing, lathering, 50 wetting or fulling agents in the dye, paper, textile and leather industries. The products of the invention may also be employed in combination with neutral, acid or basic salts which serve to 55 increase their emulsifying, wetting and dispersing power, such as, for example, sodium sulphate, sodium chloride, sodium acetate, mono- di- and tri-sodium phosphates, sodium carbonate, sodium bicarbonate, and similar compounds of the other 60 alkali metals or of ammonium. Other additional materials with which the products of the invention may be combined are bleaching and disinfectant agents such as persulphates, percarbonates and perborates; filling materials such as 65 talc, marble-dust, and starch; adsorbing materials such as suitable clays, e. g. fuller's earth; protective colloids or dispersing agents such as gum tragacanth, gall acids and their derivatives, agar-agar, glue, methyl cellulose, sulphite cellulose lyes, sodium cellulose phthalate, calcium saccharate, albumin, sodium cellulose glycolate, gelatin, natural and artificial resins, derivatives of chlorestericine, phosphatides, geloses, natural and artificial waxes, wool waxes, solvent and softening 70

75

agents, organic bases and their salts such as alkylolamine salts and quaternary ammonium compounds, inorganic colloids, and alkalies; and scouring materials such as kieselguhr, powdered pumice, sulphur, flour, china-clay salt and the like. Desirable results for many purposes may also be obtained by employing the sulpho acids or salts thereof produced as herein described in combination with the various acyclic, monocyclic, or complex cyclic terpenes or derivatives thereof such as, for example, limonene, dipentene, terpinolene, terpinene, phellandrene, sylvestrene, pinene, bornylene, sabine and their alcoholic, ketonic and aldehydic derivatives. It will be apparent, furthermore, our new products may be combined with a wide variety of other additional materials which possess washing, cleansing, emulsifying, wetting, dispersing, adsorbing, lathering, bleaching, germicidal and bactericidal powers. They may likewise have incorporated therewith artificial or natural perfuming substances, many of which in themselves may possess detergent properties of some value.

In addition to the advantages above enumerated the invention is further advantageous in that it offers a large outlet for cheap raw material such as oils and fats from natural sources and those obtainable in large quantities as by-products from the textile, and leather industries, from fish oils, and a large number of other sources. Moreover, many of these by-products have been of relatively little value or usefulness heretofore because of the bad odor associated therewith. By converting these raw materials to olefines for use in the present process odor ceases to be a serious factor.

In the practical application of the products of the invention it has been noted that as a general rule their wetting properties increase with the number of carbon atoms in the unsaturated hydrocarbon employed up to about 18 carbon atoms and thereafter decrease. It has also been noted that the detergent properties of the product may vary within a relatively wide range depending largely upon the number of carbon atoms therein and the nature of the liquid in which they are employed. Thus, in soft water the detergent power increases with the number of carbon atoms in the starting material and the products prepared from unsaturated hydrocarbons containing about 20-30 carbon atoms are especially desirable. In hard water, on the other hand, products prepared from unsaturated aliphatic hydrocarbons containing less than 20 but more than about 10 carbon atoms are preferred from the standpoint of detergent power, and those prepared from the unsaturated straight chain hydrocarbons containing about 14 to 16 carbon atoms are particularly advantageous.

The chemical constitution of the products produced in accordance with the invention has not been definitely determined and therefore we do not wish to be limited by any theory in this regard or in regard to the mechanism of the reactions. In view of the enhanced wetting and detergent power of these products, however, and their greater stability in strongly alkaline and acidic solutions than products previously prepared, it appears that they are most probably true sulphonic acid derivatives. As previously pointed out, the products obtained by reaction of the unsaturated hydrocarbon with chlorosulphonic acid in the presence of a chlorinating catalyst and then hydrolyzing are somewhat better than those obtained by a similar procedure without a catalyst.

Furthermore, the procedure without the catalyst leads to the formation of a by-product oil upon hydrolysis and neutralization and the yield of final product is less. Theoretically, it appears that the treatment of the unsaturated hydrocarbon with chlorosulphonic acid without a catalyst gives rise to several reactions which proceed practically side by side so that a mixture of several substances is produced. On the other hand, when a chlorinating catalyst is employed, instead of several reactions occurring the directing influence of the catalyst causes one reaction to occur to the exclusion or practically to the exclusion of others.

A probable course of the reactions occurring when chlorosulphonic acid is reacted upon a higher olefine having a single double bond at the end of the chain in the presence of a chlorinating catalyst may be illustrated by the following equations, in which R represents a saturated hydrocarbon radical containing at least six carbon atoms:

Sulphonation

5

10

15

20

25

Hydrolysis

30

35

where M is $-\text{H}$, or a metallic radical such as $-\text{Na}$, $-\text{K}$, or the like, depending upon the hydrolyzing agent used.

Another probable course of the reactions is as follows:

Sulphonation

40

45

Hydrolysis

50

where M has the signification given it in Equation I'.

It is possible, however, that both courses of reaction given by Equations I and II may occur simultaneously so that the product is a mixture of isomers. If one of the courses of reaction predominated, or occurred practically to the exclusion of the other, it would seem that Reaction I would be favored in view of the tendency of chlorine, in the presence of a chlorinating catalyst, to attach itself to the alpha carbon atom.

55

60

If the radical R of the unsaturated hydrocarbon contains an unsaturated bond, similar reactions would probably occur at this bond. As previously indicated, these products are usually less desirable for the purposes of the invention.

65

As many apparent and widely different embodiments of this invention may be made without departing from the spirit thereof, it is to be understood that we do not limit ourselves to the foregoing examples or description except as indicated in the following claims.

70

We claim:

1. In a process for preparing surface active

75

- substances, the step which comprises reacting an aliphatic unsaturated hydrocarbon, containing at least 8 carbon atoms and having a double bond at the end of the chain, with a halogen sulphonic acid in the presence of a halogenating catalyst. 5
2. A process for preparing surface active substances, which comprises reacting an aliphatic unsaturated hydrocarbon, containing at least 8 carbon atoms and having a double bond at the 10 end of the chain, with a halogen sulphonic acid in the presence of a halogenating catalyst, and hydrolyzing the reaction product.
3. A process for preparing surface active substances, which comprises reacting an aliphatic 15 unsaturated hydrocarbon, containing at least 8 carbon atoms and having a double bond at the end of the chain, with chlorsulphonic acid in the presence of a chlorinating catalyst, and treating the reaction product with a hydrolyzing agent 20 whereby the chlorine is removed from the hydrocarbon molecule.
4. A process for preparing surface active substances, which comprises reacting an aliphatic unsaturated hydrocarbon, containing at least 8 25 carbon atoms and having a double bond at the end of the chain, with chlorsulphonic acid at a relatively low temperature, in the presence of a chlorinating catalyst, and heating the resultant product with a hydrolyzing agent.
- 30 5. A process for preparing surface active substances, which comprises reacting an aliphatic unsaturated hydrocarbon, containing at least 8 carbon atoms and having a double bond at the 35 end of the chain, with chlorsulphonic acid in an inert liquid reaction medium, and in the presence of a chlorinating catalyst, and treating the reaction product with a hydrolyzing agent whereby the chlorine is removed from the hydrocarbon molecule.
- 40 6. The process of producing a highly surface active substance, which comprises reacting an aliphatic unsaturated hydrocarbon, containing at least 8 carbon atoms and having a double bond at the 45 end of the chain, with chlorsulphonic acid at a temperature within the range of about $-10-+35^{\circ}\text{C}.$, in an inert liquid reaction medium which is a solvent for the unsaturated hydrocarbon, in the presence of a chlorinating catalyst, then removing the reaction medium, heating the 50 remaining product with a hydrolyzing agent, neutralizing the resultant product and recovering the neutralized product.
7. The process of preparing surface active substances, which comprises reacting a straight 55 chain unsaturated aliphatic hydrocarbon, containing at least 8 carbon atoms and having a single double bond at the end of the chain, with chlorsulphonic acid in proportions corresponding to about 1 to 2 mols of chlorsulphonic acid 60 per mole of unsaturated hydrocarbon, in an inert solvent reaction medium boiling below about $100^{\circ}\text{C}.$, at a temperature within the range of $-10-+35^{\circ}\text{C}.$, in the presence of a chlorinating catalyst, adding to the resultant product water and 65 about one equivalent of alkali metal hydroxide for every equivalent of chlorsulphonic acid used, the proportions of water corresponding to an aqueous solution of said alkali metal hydroxide having a concentration of about 2-20%, heating the product obtained to a temperature of about $100^{\circ}\text{C}.$ to effect hydrolysis thereof and at the same time to remove the reaction medium, neutralizing the hydrolyzed product with a mineral acid and recovering the neutralized product substantially free from inorganic salts. 5
8. In a process of preparing surface active substances, the step which comprises reacting an aliphatic unsaturated hydrocarbon containing 8 to 18 carbon atoms, inclusive, and having a double bond at the end of the chain, with chlorsulphonic acid in the presence of a chlorinating catalyst. 10
9. In a process of preparing surface active substances, the step which comprises reacting an aliphatic unsaturated hydrocarbon containing 20 to 30 carbon atoms, inclusive, and having a double bond at the end of the chain, with chlorsulphonic acid in the presence of a chlorinating catalyst. 15
10. In a process of preparing surface active substances, the step which comprises reacting branched chain aliphatic unsaturated hydrocarbons containing at least 8 carbon atoms and having a double bond at the end of the chain, with chlorsulphonic acid in the presence of a chlorinating catalyst. 20
11. In a process of preparing surface active substances, the step which comprises reacting an aliphatic unsaturated hydrocarbon containing at least 8 carbon atoms and having a double bond at the end of the chain, with chlorsulphonic acid in the presence of a chlorinating catalyst selected from the group consisting of inorganic oxides and salts of antimony, copper, manganese, 30 iron, vanadium, aluminum, alkali metal iodides and free iodine. 35
12. The process of claim 8 in which the reaction product is subsequently heated with a hydrolyzing agent selected from the class consisting of dilute acids and dilute alkalies under conditions adapted to replace chlorine atoms by hydroxyl groups. 40
13. The process of claim 11 in which the reaction product is subsequently heated with a hydrolyzing agent selected from the class consisting of dilute acids and dilute alkalies under conditions adapted to replace chlorine atoms by hydroxyl groups. 45
14. The process of claim 8 in which the aliphatic unsaturated hydrocarbons correspond to the olefines obtainable by the dehydration of alcohols from coconut oil. 50
15. The process which comprises reacting an aliphatic unsaturated hydrocarbon containing at least eight carbon atoms and having a double bond at the end of the chain with chlorsulphonic acid at a temperature below about $50^{\circ}\text{C}.$, in an inert solvent for the unsaturated hydrocarbon in the presence of a chlorination catalyst, then removing the solvent, heating the remaining product with a hydrolyzing agent, neutralizing the resultant product, and recovering the neutralized product. 60
